CLAIM

The ornamental design for a bicycle frame, as shown and
described.

DESCRIPTION

FIG. 1 is a perspective view of a bicycle frame embodying
our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The broken lines in the drawing delineate segments of
bicycle frame that form no part of the claimed design.

1 Claim, 6 Drawing Sheets
